DESIGN FOR A CASKET OR ANALOGOUS ARTICLE

Raymond Larson, Chicago, Ill.

Application April 11, 1936, Serial No. 62,062

Term of patent 7 years

To all whom it may concern:

Be it known that I, Raymond Larson, a citizen of the United States, residing at 2207 North Lamon Avenue, Chicago, Illinois, have invented a new, original, and ornamental Design for a Casket or Analogous Article, of which the following is a specification, reference being had to the accompanying drawing, forming part thereof,

Fig. 1 is a side elevational view of a casket embodying my new design, and

Fig. 2 is an end elevational view of the same.

I claim:

The ornamental design for a casket or analogous article as shown.

RAYMOND LARSON.
